F. WEINBERG.
FUEL FEED APPARATUS.
APPLICATION FILED SEPT. 24, 1917.

1,292,183.

Patented Jan. 21, 1919.

UNITED STATES PATENT OFFICE.

FREDERICK WEINBERG, OF DETROIT, MICHIGAN.

FUEL-FEED APPARATUS.

1,292,183.

Specification of Letters Patent. Patented Jan. 21, 1919.

Application filed September 24, 1917. Serial No. 192,913.

To all whom it may concern:

Be it known that I, FREDERICK WEINBERG, a citizen of the United States, residing at Detroit, county of Wayne, State of Michigan, have invented a certain new and useful Improvement in Fuel-Feed Apparatus, and declare the following to be a full, clear, and exact description of the same, such as will enable others skilled in the art to which it pertains to make and use the same, reference being had to the accompanying drawings, which form a part of this specification.

My invention relates to fuel feed apparatus for internal combustion engines and an object of my improvements is to provide an apparatus including a reservoir for the fuel which shall supply the fuel even when an opening is formed through the wall of the reservoir by being pierced by a bullet or otherwise, as for instance, the tank in an aeroplane being damaged by springing seams during a rough landing or a slight fall. Another object of my improvement is to render the fuel reservoir explosion-proof.

I attain these objects illustrated in the accompanying drawings, in which:

Figure 1 is a side elevation partly in section on the line A—A of an apparatus embodying my invention and so much of an internal combustion engine as is necessary to illustrate its connection therewith.

Fig. 2 is a detail sectional view to an enlarged scale of the vacuum producing apparatus.

Fig. 3 is a detail sectional view of a portion of the wall of the supply tank or reservoir *a*.

Figs. 4, 5, 6 and 7 are modified forms of the suction producing apparatus.

Fig. 8 is a modified construction of the liquid fuel reservoir.

a is the tank or reservoir which holds the supply of liquid fuel. The tank *a* is preferably provided with three inclosed walls, *a*² of steel, *a*³ of cork, and *a*⁴ of rubber or it may be of steel. Of course, a material having similar properties may be substituted for those specified for the various walls of the tank. For instance instead of rubber, asphalt, felt, pulp, asbestos or similar elastic material may be used and it is desirable that such material be treated either with sodium silicate or carbon tetrachlorid and instead of steel any other metallic or non-metallic body that will not be acted on by the fuel

and its contaminations, for instance brass or bronze or aluminum may be used.

b is the engine having an intake pipe or manifold *b*² drawing its supply through a carbureter *b*³ and having an exhaust pipe *b*⁴. The tank *a* is located at a lower level than the carbureter *b*³. *c* is a centrifugal pump having a supply pipe *c*² extending from its intake to the bottom of the tank *a*. *c*³ is a foot valve in the pipe *c*². The delivery of the pump *c* is through a pipe leading to the carbureter *b*³ and this carbureter is supposed to be supplied with the conventional constantly level apparatus which will prevent the flooding of the engine by the constantly running pump *c*. The liquid supply pump is of the impelling type and has a certain amount of slip. When the carbureter needle valve shuts off the supply the slip of the inefficient pump will prevent the rising of the pressure to any considerable extent. *e* is an extension of the exhaust pipe or manifold *b*⁴. In the extension *e* is placed an interior tube *e*² forming a Venturi contraction. The tube *e*² is pierced by apertures *e*⁴ near its narrowest portion. There is a wire gauze *e*³ interposed between the tubes *e*² and *e*. *d* is a suction pipe having its bore communicating with the interior of the exhaust pipe *e* between said pipe and the tube *e*². By the above described apparatus a vacuum is continuously drawn in the reservoir *a* when the engine is in operation and the amount of this vacuum is regulated by a conventional differential pressure valve indicated at *d*² and interposed in the pipe *d*. The differential pressure valve may be omitted if the source of suction is small and approximately constant as shown in the modification Fig. 7, which is also the case when the Venturi tube is solely operated by the draft created by the moving of the machine through the air. This is, for instance, the preferable type of the suction producing means as used on an aeroplane.

Instead of the vacuum producing apparatus *e* *e*² a centrifugal fan or pump may be used, as shown in Fig. 4, or the vacuum produced in the intake manifold may be used either directly, as shown in Fig. 6, or through a Venturi attachment as shown in Fig. 5, or the draft from the airplane propeller may be projected through a Venturi tube *g* to produce the vacuum, as shown in Fig. 7, which action may be replaced in part

or entirely by the draft of air due to the speed of the aeroplane.

The vacuum drawn in the reservoir *a* should be a little greater than that represented by static head equal to the height of said tank or reservoir.

The operation of the above described device is as follows:

The engine being set in motion the pump 10 *c* supplies the fuel to the carbureter *b*³ in the usual way, at the same time a partial vacuum is drawn and maintained in the reservoir *a*. Now if the wall of the tank *a* is pierced by a bullet as indicated at *x* the cork 15 *a*³ will partly close the aperture and the rubber cover *a*⁴ will even more approximately close said aperture. The vacuum in the tank *a* being greater than that represented by the head of liquid above the aperture *x* no liquid 20 will run out and the loss of fuel and danger of fire and leakage will therefore be avoided. Should a flame be brought in contact with the aperture, such flame will be drawn in and extinguished inside of the fuel and 25 quenched. It is advisable to treat the cork with sodium silicate to prevent deterioration thereof and to prevent it being set on fire by an incendiary bullet.

While a tank having a single compartment 30 may be used nevertheless if two holes are pierced in the same compartment at different levels the liquid therein would be liable to run out to the level of the lower hole. I have, therefore, divided the tank *a* into a 35 number of compartments communicating with each other by restricted passages at their lowest points and connected each of said compartments independently by pipes *d*, *d*¹, *d*³, *d*⁴, with a source of vacuum as 40 with the interior of the Venturi tube *e*². Each of these compartments may be pierced with a single hole without losing the liquid therefrom. The compartment plates act also as baffle plates and prevent the splashing of 45 the fuel. In some cases to effect correct balancing of the machine the different compartments may be placed in different parts of the machine, in which case they are interconnected by means of pipes. A thin disk 50 *x*² of suitable material may be placed over the hole and will be retained there by suction, thus closing the opening. This will only be required in case of damage caused by an explosive bullet leaving a large hole 55 in the wall.

The cork has the property of an intermediate cushion allowing the torn steel edges on the exit side of the bullet to become fully embedded in it and still presenting a 60 pierced but substantially smooth surface toward the rubber. Instead of cork fabric may be used. The two walls, the fabric and the rubber being preferably cemented together. When a bullet enters the liquid con-

taining tank the edges of the aperture made 65 by it sometimes turn outward due, as I suppose, to the pressure caused by the energy of the bullet. To mitigate the injurious effect of this action the inside wall should be made of material having little strength, and 70 be much thinner than the thickness of the combined elastic material covering it so as not to penetrate these. This is important, also, for the disk or sheet cover *x*² will only 75 stick and close the aperture when a substantially smooth surface is presented. In warfare for instance, a tracer, an explosive, and an incendiary bullet are fired in quick succession and in a fraction of a second and it is evident that either or any of them, or 80 several of them, may strike the tank. While the cover is sufficient for the ordinary steel and incendiary bullet it is of no avail against the attack of the explosive bullet. The latter will tear large holes into the wall 85 of the tank and the only way to secure a temporary safeguard is by applying a flexible disk or sheet *x*² which may either be done by hand or automatically.

What I claim is:

1. In a fuel feed apparatus, the combination of a carbureter, a tank located at a lower level than said carbureter and having normally air-tight walls for containing the liquid fuel, means for withdrawing the fuel therefrom, and supplying it to said carbureter, and means for maintaining a partial vacuum in said tank.

2. In a fuel feed apparatus, the combination of a carbureter, a tank located at a lower level than said carbureter and having normally air-tight walls for containing the liquid fuel, means for withdrawing the fuel therefrom and supplying it to said carbureter, and automatic means for maintaining 105 a partial vacuum in said tank.

3. In a fuel feed apparatus, the combination of a carbureter, a tank located at a lower level than said carbureter and having normally air-tight walls for containing the liquid fuel, means for withdrawing the fuel therefrom and supplying it to said carbureter, and automatic means operated by the engine for maintaining a partial vacuum in 110 said tank.

4. In a fuel feed apparatus, the combination of a carbureter, a tank located at a lower level than said carbureter and having normally air-tight walls for containing the liquid fuel, means for withdrawing the fuel therefrom and supplying it to said carbureter, means for maintaining a partial vacuum in said tank, and means for adjusting the degree of said vacuum.

5. In a fuel feed apparatus, the combination of a carbureter, a tank having normally air-tight walls for containing the liquid fuel, means for withdrawing the fuel therefrom, means for maintaining a partial vacuum in

said tank, and adjustable means for automatically regulating the degree of said vacuum.

6. In a fuel feed apparatus, the combination of a tank having air-tight walls for containing the liquid fuel, means for withdrawing the fuel therefrom, and means for maintaining a partial vacuum in said tank, said tank being divided into a number of 10 communicating compartments, each compartment communicating independently with a source of vacuum.

7. In a fuel feed apparatus, a supply tank having two walls spaced from each other, 15 elastic material in the space between said walls, and means for maintaining a vacuum in said tank.

8. In a fuel feed apparatus, the combination of a main liquid supply tank, a carbureter, a conduit leading from said tank to 20 said carbureter, and a pump in said conduit adapted to impel the liquid from the tank to the carbureter with a limited force and to allow the liquid to bypass the impelling 25 pump blades when a certain pressure has been attained.

9. In a fuel feed system, the combination of a main liquid supply tank, a carbureter, means for feeding said carbureter from said 30 supply tank, and means for reducing the pressure in said supply tank consisting in part of a Venturi tube.

10. In a fuel feed system, the combination of a main liquid supply tank, a carbureter, 35 a supply conduit leading from said tank to said carbureter, means for reducing the pressure in said supply tank consisting in part of a Venturi tube, said Venturi tube having

an outer and an inner casing with a space therebetween, said conduit connecting with 40 the space between said outer and inner casing and with said tank.

11. In a fuel feed apparatus, the combination of a fuel tank, means for maintaining a vacuum therein, said tank having a perforation through its wall and a disk applied to said perforation and held there by atmospheric pressure.

12. In a fuel feed apparatus, the combination of a tank, means for maintaining a 50 static vacuum in said tank, said means being adapted to produce a dynamic vacuum upon a perforation being made in said tank.

13. In a liquid fuel supply apparatus, the combination of a liquid supply tank having 55 a wall consisting of solid and elastic materials, and means for maintaining a reduced pressure in said tank.

14. In a fuel feed apparatus, the combination of a supply tank, a carbureter, a conduit 60 leading from said tank to said carbureter, a float controlled valve adapted to control the passage of liquid through said conduit, and a centrifugal pump in said conduit adapted to impel the liquid from said tank to said 65 carbureter through said conduit.

15. In a fuel feed apparatus, the combination of a carbureter, a tank having normally air-tight walls for containing the liquid fuel, means for withdrawing the fuel from 70 said tank and supplying it to said carbureter, and a source of suction communicating with said tank above the fuel therein.

In testimony whereof I sign this specification.

FREDERICK WEINBERG.
